UNITED STATES PATENT OFFICE.

FREDERICK B. WATKINS, OF LOS ANGELES, CALIFORNIA.

SIGNALING DEVICE.

Application filed January 4, 1921. Serial No. 434,981.

To all whom it may concern:

Be it known that I, FREDERICK B. WATKINS, a citizen of the United States, residing at the city of Los Angeles, county of Los Angeles, and State of California, have invented new and useful Improvements in Signaling Devices, of which the following is a specification.

My invention relates primarily to an electrical automobile signal, and the first object thereof is to produce a signal which when viewed from any point of the compass is instantly interpreted, independent of distance, as to the motion intended. The second object of the invention is to provide a signal which shows the relative degree of danger and safety to which the observer of the signal is exposed. The third object of my invention is to provide a compact signal which can be concentrated at a conspicuous and vulnerable point of the automobile and afford protection to this point by producing a signal visible to motorists approaching from all points of the compass. The fourth object of my invention is to provide an electrical signal which functions by day as well as by night. The fifth object is to provide means for simplicity of operation.

I accomplish these objects by the signal described herein and illustrated in the accompanying drawings forming a part hereof, in which:

Fig. 1 is a sectional view S^1 , S^1 of Fig. 2 or Fig. 6 and shows the practically encircling perimeter of glass panels 13.

Fig. 2 is a sectional elevation S^2 , S^2 of Fig. 1 showing one quarter of the signal being practically one compartment, the other three being duplicates.

Fig. 3 is a plan view of the switch with the fiber button on the end of the "knife" of the switch removed showing the upper double pointed contacts.

Fig. 4 is a sectional elevation S^4 , S^4 of Fig. 3 showing the method of supporting the oscillating switch knife tube 45 and the method of fastening the double pointed contacts 41 to the fiber cylinder 42 by binding posts 52.

Fig. 5 is a plan of the top and bottom guide plates 50 and 51 of the switch.

Fig. 6 is a general elevation of the complete assembly of the signal viewed from practically any point of the compass, and shows the glass panels 13 which project a

long rectangular band of light on any vertical plane.

Fig. 7 is an elevation of the circuit maker.

Fig. 8 is a sectional view S^8 , S^8 of Fig. 7 showing the method of fastening plate 43 in the fiber cylinder 42.

Fig. 9 is an elevation and plan view, *a* and *b* respectively, of a detached contact 41.

Fig. 10 shows a general wiring diagram. The top and bottom contacts are shown in the same horizontal plane to facilitate showing the contacts made in giving different signals.

Fig. 11 illustrates several observations made by motorists approaching a street crossing when motorist M signals different intended moves; also, the relative degree of danger and of safety that the signal displays to the observer.

In the drawings the main body of the signal is comprised of a metal box with top 5, and bottom 6, and divided into four equal compartments by the dividing walls 7, 8, 9 and 10, and preferably octagonal in plan view. The octagonal shape is used for simplicity of construction. The ideal signal would have a circular perimeter of glass.

A cylindrical tube 11 connects the top and bottom walls. The glass panels 13 form the outer sides of the box. Stops 14 are turned from the top and bottom walls and with the aid of felt packing 15 keep the glass panels in position. The bottom of each compartment is painted black to absorb any sunlight that might enter below the overhanging hood 16. The other walls of each compartment are of polished metal.

The surfaces of the glass panels, and especially the inner, are preferably frosted to aid in giving a uniform diffusion of light. The bands of felt 15 are glued to each glass panel where it comes in contact with the metal and protect it from the same. In each compartment there are two electric lights 17 and 18, of different colors, either of which is capable of strongly illuminating the whole compartment. The colors used in this case being red and green. The lower four lights are red. The upper four lights are green. The sockets 19, for each set of four lights, are fastened in manifold plates 20 and 21. The manifold plates are held centrally by slipping them over the central pipe 24. A hole in the top and the bottom of each compartment permits the sockets to enter the compartments in

their proper positions. Plate 5 forms the top of the compartments. Plate 6 forms the bottom of the compartments. A bottom casing 22 partly supports the bottom of the box and has turned up ends which afford outer walls for keeping the felt packing and glass panels in place. It also protects the lower part of the signal from the weather. The lower end of casing 22 rests upon and is supported by base plate 23 which is screwed upon the tie pipe 24 thru which the wires 34 pass to the lights. A hood 16 primarily affords protection against sunlight for the glass panels, besides casting a shadow over them, thus making possible the functioning of the signal by day as well as by night. A flanged octagonal ring 25 keeps the upper ends of the glass panels in place. A pierced cap 26 rests upon the top of the hood 16 and is held positioned by collar 27 which is soldered to pipe 28. Pipe 28 screws into a connector cap 29. Cap 29 is screwed upon the top of the pipe 24.

25 In the case of fastening the signal to the fender of an automobile the plate 23 is bolted to the fender 30 by bolts 31. Pipe 24 is screwed into plate 23. Casing 22 is then put in place. Sleeve 32 is slipped over pipe 24 with the holes 33 in pipe 24 and sleeve 32 in register so as to permit connecting wires 34 to run to the bottom lights. Manifold plate 20 is next put in place. Connections to the bottom sockets are made and then the main box is slipped over pipe 24. The top manifold 21 is put in place and the cap 29 screwed down. The lights are now put in place. The glass panels follow and then the hood is set on with the octagonal ring 25 slipped down over the felt packing. Pipe 28 is then screwed into cap 29 thereby holding the hood firmly in place. Pipe 28 may be allowed to stand several inches above collar 27 to enable fastening a "vanity glass" to it, or to hold flags, etc. Wires 34, one from each light socket, run to a switch placed convenient to the driver's seat, and are there connected each to a separate contact 41 by binding posts 52. The upper contacts are shown in Fig. 3. The lower contacts are a duplicate of the upper ones. The return wires are all grounded and are not shown. The common return wire to the battery is shown grounded to the metal box at Z, Fig. 10. The contacts 41 are connected to fiber cylinder 42 by binding posts 52. A metal plate 43 is mounted centrally in cylinder 42 and is electrically connected by wire 44 to a source of electrical energy. Plate 43 is rigidly fastened to cylinder 42 by binding post 53 and slots shown in Figs. 7 and 8. A switch knife tube 45 passes thru plate 43 and has a collar 46 above and a square collar 47 below plate 43. A spring 48 rests upon plate 43 and bears against

collar 46 thereby normally holding tube 45 out of contact with the points 41, with collar 47 engaging plate 43, thereby electrically connecting tube 45 with plate 43. A fiber button 49 prevents the current from passing to the driver when the switch is operated. Cylinder 42 has a fiber top 50 and a fiber bottom 51 in each of which are right-angled guide-ways to guide tube 45 when the switch is operated. A bracket 59 is secured to cylinder 42 by bolts 55 to facilitate its attachment to a suitable part of the machine, which is preferably the steering post. In using my signal the division walls 7, 8, 9 and 10 are placed parallel to and at right angles to the sides of the machine X and Y, Fig. 10. The signal would be placed preferably on the top of the left front fender. The fender should stand high and well forward so that the signal is easily visible from either side as well as from the front and rear. The signaling switch is placed so that the switch knife tube can be oscillated parallel to and at right angles to the sides of the automobile X and Y, Fig. 10.

For a left turn the top of the switch knife tube is thrown to the left. In Fig. 10 the plan of the contacts g^1 , g^2 , g^3 and g^4 , shown at T, represents the top contacts of the circuit maker and breaker. A wire connects each one of these double pointed contacts with a green colored electric light positioned as shown in Fig. 10. At U, Fig. 10, is shown a plan of the bottom contacts as seen by moving the top plan to one side. A wire connects each one of these lower double pointed contacts with a red colored electric light positioned in a compartment of the signal as shown. In dotted lines, the switch knife tube is shown positioned for a turn to the left. The upper half of the switch knife tube takes position L where it makes contact with contacts g^2 and g^3 thereby causing current to be sent thru green lights G^2 and G^3 positioned in compartments on the right side of the signal and lighting the right half of the signal green. At the same time the lower half of the switch knife tube takes the position shown in dotted lines at L' , as the tube pivots about the plate 43 centrally located in fiber cylinder 42. In this position L' the switch knife tube makes contact with r^1 and r^4 whereby the red lights R^1 and R^4 light the left half of the signal red. There is thus produced a band of light completely encircling the signal, half red and half green. The projection of this band of light on any vertical plane is a long rectangular band of light as shown by glass panels 13, Fig. 6. The encircling band of light is divided into two colors by a vertical plane passed thru the center of the signal. Motion is indicated as taking place from the green to the red. The signal observed from practically any point of the compass dis-

plays a long band of light part red and part green. This simulates an arrow with a red head and a green tail. Direction is indicated as the arrow points from the green tail to the red head.

Fig. 11 gives a practical demonstration of signals observed from four points of the compass A, B, C and D when motorist M, approaching a street crossing, signals an intended change of line of motion, continued line of motion or a stop. At each of the points of observation, A, B, C and D, are four rectangles numbered 1, 2, 3 and 4, being the projections of the light of the signal visible to the observer for the different signals given by M. The darkly shaded portion of the rectangles represents the red light and the lightly shaded portion the green light. No. 1 rectangles show a signal for an intended turn to the left; No. 2 is for a turn to the right; No. 3 indicates intention to continue in the same line of motion; No. 4 signals a stop or motion to the rear.

At M, Fig. 11, is shown the ideal plan of the four compartments of the signal lighted for a turn to the left. The darkly shaded left half of the signal is red and the lightly shaded half is green. It is assumed that the signal is placed on the left front fender of the automobile. At A projection No. 1 is what the observer A sees coming up from behind with the intention of passing M. This indicates that the intended line of motion of M is practically directly across the line of motion pursued by A as shown by the arrow. At B the observer sees projection No. 1 which points into the direction indicated by the arrow at B. Thus motorist M intends assuming the same line of motion pursued by B. By noting the proportion in which the colors are visible it is also seen that the observer at B is looking fairly well into the green tail of the signal and thus the indicated motion must lie practically ahead. At C the observer sees by projection No. 1 that the intended line of motion of M is directed across his path. At D the observer is looking practically into the red head of the signal showing that the intended line of motion of M is practically in a direction opposite that pursued by D.

For a turn to the right the top of the switch knife tube is thrown to the right, into the position R, Fig. 10, making contact with g^1 and g^4 lighting green lights G^1 and G^4 on the left side of the signal. At the same time the lower half of the switch knife tube occupies the position R' making contact with r^2 and r^3 , lighting red lights R^2 and R^3 on the right side of the signal. The observed projections No. 2 at A, B, C and D show the results that would occur were M to signal a turn to the right.

For a signal to show intended continued

line of motion the top of the switch knife tube is thrown forward to the position F, Fig. 10. Contact is made with g^3 and g^4 lighting green lights G^3 and G^4 in the rear half of the signal. At the same time the lower half of the switch knife tube moves to position F' where it makes contact with r^1 and r^2 , lighting red lights R^1 and R^2 in the front half of the signal. The observed projections No. 3 at A, B, C and D show the results that would occur were M to signal intended continued line of motion, or crossing of the intersections.

For intended negative forward acceleration, that is, a slowing up or stop or motion to the rear, the top of the switch knife tube is thrown to the position S, Fig. 10. Contact is made with g^1 and g^2 lighting green lights G^1 and G^2 in the front half of the signal. At the same time the lower half of the switch knife tube moves to position S' where it makes contact with r^3 and r^4 lighting red lights R^3 and R^4 in the rear half of the signal. The observed projections No. 4 at A, B, C and D, Fig. 11, show the results that would occur were M to signal an intended negative forward acceleration.

The working principle of the signal also shows the relative degree of danger and of safety to the observer by the relative proportions of red and green respectively seen by the observer. By danger to the observer is meant the observer being run into by the signaller. When the observer sees practically nothing but a red signal motion is directed practically toward the observer and the danger to the observer is a maximum. When the observer sees practically nothing but a green signal the intended motion is directed practically away from the observer and the danger to the observer is a minimum. For example:—In Fig. 11 motorist M is preceding observer A up the street as indicated by the arrows. M signals an intended left turn which A observes at rectangle No. 1. A intends passing M but by the time A reaches the point A', M is at M' and the signal now confronting A' is one of increased danger as shown by rectangle No. 1'. At P the pedestrian, or observer, sees by rectangle No. 1 that M intends making a left turn and that the apparent degree of danger and safety is 50—50, the proportion of red to green being practically 1 to 1. By the time M has reached the position M' P sees rectangle No. 1' which shows a state of minimum danger. The signal has thus automatically indicated to the observer the relative degree of danger and of safety for each instantaneous position occupied by the signal in passing thru the limits mentioned.

On entering a street intersection the signal protects the motorist by being preferably located at the top of the left front fender of the automobile. The signal, be-

sides showing the intended motion of the motorist, shows the presence of the automobile entering a street intersection to the motorist approaching from either side as well as from the front and rear. It is assumed that the motorist displays a signal on approaching the intersection showing his intended movement. In Fig. 11 motorist M signals some intended motion as he is about to enter the street intersection. Motorists at B and D will see either one of the four signals given by M, and shown by the rectangles 1, 2, 3 and 4, and be warned of the presence of an automobile, thus protecting motorist M. This is especially important at dark street intersections.

At "blind corners," with the signal set on the top of the left front fender, it is apparent from the diagram, Fig 11, that the observers B and D will see the signal given by M before the driver M comes into view. Automobiles emerging suddenly into view from behind intervening vehicles or objects will indicate their intended motion immediately due to the compactness of the signal, located at a conspicuous point and visible from all points of the compass.

Having described my invention I claim:—

1. An electrically operated signaling device comprising a housing divided into four equal compartments, two lights in each com-

partment of different colors, and a switch adapted to light lights of one color in any two adjacent compartments and of a different color in the other two compartments at the same time.

2. An electrically operated signaling device, a housing containing a continuous glass perimeter divided into four equal compartments, two lights of different colors in each compartment; and means under the control of the driver for illuminating any two adjacent compartments of the same color and the other two compartments of a different color at the same time, whereby signals, indicating the intended movements of the vehicle, are visible from all points of the compass.

3. An electrically operated signaling device comprising a housing divided into four equal compartments; means under control of the driver of the vehicle for displaying bands of light of two colors to indicate the intended movements of the automobile whereby the relative degree of danger and of safety, that the observer of the signal is exposed to, is automatically indicated.

In witness that I claim the foregoing I have hereunto subscribed my name this 29th day of December, 1920.

FREDERICK B. WATKINS.
